PENNSYLVANIA.

RAIL JOINT.

Application filed June 28, 1928. Serial No. 288,891.

- This invention relates to rail joints and more particularly to a rail joint for railway rails and has for one of its objects the provision of a rail joint that is provided with 5 definite points of contact and intermediate spaces of contraflexure, for the purpose of transmitting and distributing the excess loads and reversing stresses due to rolling wheel loads.
- 10 Another object is to provide a rail joint of greater torsional resistance than the present designs of rail joints in common use.
- A further object is to provide a rail joint that will function properly without regard to 15 design of rail head and fishing angles.
- A still further object is to provide a rail joint that is materially lighter in weight than the usual forms of rail joints of the same strength.
- 20 During the past several years railway rails have been greatly improved by changes in section, composition, and methods of manufacture so as to greatly increase the wearing qualities and life.
- 25 The joints for the rails have not been improved at the same rate, however, and consequently the failure of joints and rails at or near the joints has increased at an alarming rate.
- 30 A rail, as mounted in a track, is a continuous beam with theoretically fixed points of support definitely located (over the ties) and with intermediate spaces of unrestricted contraflexure (between the ties).
- 35 The usual design of joints at present is intended to support or reenforce the ends of the rails throughout the length of the joint, without allowing definite points of contact and intermediate spaces of contraflexure.
- 40 These joints transmit the excess load and the constantly reversing stresses through the joint members to the ties supporting the ends of the rails, instead of carrying them to the adjoining rail for more nearly equal distribution to all the ties and, consequently, substantially all the stresses and loads must be taken up in the joint with the resultant failures set forth above.
- The present invention provides for definite 50 points of contact and intermediate spaces of contraflexure in the joint, so that the loads and stresses are distributed throughout the rails beyond the joint and consequently less

failure of the joints and the rails adjacent to the joints is experienced. 55

In the drawings:

Figure 1 is a side elevation of a rail joint constructed in accordance with this invention.

Figure 2 is a transverse sectional elevation taken on the line II—II of Figure 1.

Figure 3 is an end elevation showing the combined chair and fish-plate member of the joint as it is rolled and prior to being forged and shaped. 65

Figure 4 is a similar view showing the chair and fish-plate member after it has been forged by a bull-doing machine to form the alternate depressions and projections in the fish-plates. 70

Figure 5 is a fragmentary detail view partly in section, illustrating the wedges adjacent the ends of the combined fish-plate and chair.

Figure 6 is a similar view illustrating the wedge adjustment at the center of the combined fish-plate and chair. 75

Referring more particularly to the drawings the numeral 2 designates the ties of a railway, and the numeral 3 designates the rails which are of the standard T-head type. 80

The abutting ends of the rails 3 are joined by the combined chair and fish-plate member A of this invention, which is preferably of an integral or one-piece construction. 85

The combined chair and fish-plate member A comprises a base or chair plate portion 5 and integral fish-plate portions 6 which extend inwardly, as at 6^a, so as to overlie the base flanges of the rails and then extend upwardly parallel with the webs of the rails to form web engaging portions 6^b. 90

The fish-plate portions 6 have their portions 6^a overlying the base flanges of the rails 2 shaped by forging or in any other suitable manner, to form alternate projections and depressions 7 and 8, thereby providing definite points of contact of the fish-plate members 6 with the rail base flanges and intermediate spaces of contraflexure; and 100 producing corresponding depressions 7^a and elevations 8^a on the exposed faces.

The fish-plate portions 6 are provided with a plurality of openings 9 adjacent their lower edges, that is, adjacent their juncture with the chair or base-plate 5, and the openings 9

in the opposite fish-plates are in alinement. There are preferably three of the sets of openings 9 provided, one set of which is provided adjacent each end of the fish-plates, and one set of which is provided at approximately the vertical center of the fish-plates. The openings 9, adjacent the ends of the fish-plates, are arranged so as to underlie at least a portion of one of the projections 7, and the 10 central openings 9 wholly underlie one of the projections 7.

A pair of oppositely directed wedge members 10 are mounted in each of the sets of openings 9 adjacent the ends of the fish-plates 6 and project and are adapted to be driven inwardly to force the rails 3 into rigid engagement with the projections 7 of the fish-plates 6.

The ends of the rails 3 meet or abut adjacent the center of the openings 9 at the center of the fish-plates and, since it is desirable to provide individual means for forcing the separate rails up into engagement with the fish-plates 6, three wedges 12, 13 and 14, are mounted in the openings 9 at the center of the fish-plates. The lower wedge 12 is substantially the complete width of the center openings 9 and underlies the ends of both rails, while the wedges 13 and 14 are directed 30 opposite to and are only one-half the width of the wedge 12, so as to underlie the ends of the separate rails. Thus driving in of the wedges 13 and 14 will permit the separate adjustment of the ends of the rails 3.

35 The several wedges 10, 12, 13 and 14 serve to provide definite points of contact between the base flanges of the rails and the chair or base-plate 5 and cooperate with the projections 7 and depressions 8 of the fish-plates to 40 provide definite points of contact and intermediate spaces of contraflexure for the rails, so as to transmit and distribute the excess loads and reversing stresses due to the rolling wheel loads to the adjoining rail body 45 for distribution to all the ties.

The fish-plates 6 are provided with the usual bolt openings through which the usual joint bolts 16 are passed to secure the rails and fish-plates together.

50 The combined chair and fish-plate member A lends itself readily to commercial manufacture, since it may be principally formed by rolling. A section like that of Figure 3 is first rolled, at which time the chair or base portion 5 is arched. The section is then cut to length and forged in what is known as a bull-dozer machine to form the alternate projections and depressions 7 and 8.

60 The openings 9 for the wedges and the holes for the bolts 16 may be punched either before or after the forging operation, and the structure is then complete except that it must be bent into final shape by flattening out the arched chair or base portion 5.

65 While we have shown and described one

specific form of our invention, it will be understood that we do not wish to be limited thereto since various modifications may be made without departing from the scope thereof as defined in the appended claims. 70

We claim—

1. A rail joint comprising, in combination, a pair of rails, a combined chair and fish-plate member connecting said rails, said combined chair and fish-plate member comprising a base portion and fish-plate portions, said fish-plate portions having inwardly extending portions overlying the base flanges of said rails and upstanding web engaging portions, said inwardly extending portions of said fish-plate portions overlying the base flanges of said rails being provided with alternate projections and depressions so as to form definite points of contact and intermediate spaces of contraflexure for the rails. 80

2. A rail joint comprising, in combination, a pair of rails, a combined chair and fish-plate member connecting said rails, said combined chair and fish-plate member comprising a base portion and fish-plate portions, said fish-plate portions having inwardly extending portions overlying the base flanges of said rails and upstanding web engaging portions, said inwardly extending portions of said fish-plate portions overlying the base flanges of said rails being provided with alternate projections and depressions so as to form definite points of contact and intermediate spaces of contraflexure for the rails, 90 and means for forming a plurality of spaced points of contact between said base portion of said combined chair and fish-plate member and the under side of the base flanges of said rails, said means being mounted below said projections on said fish-plates. 100

3. A rail joint comprising, in combination, a pair of rails, a combined chair and fish-plate member connecting said rails, said combined chair and fish-plate member comprising a base portion and fish-plate portions, said fish-plate portions having inwardly extending portions overlying the base flanges of said rails and upstanding web engaging portions, said inwardly extending portions of said fish-plate portions overlying the base flanges of said rails being provided with alternate projections and depressions so as to form definite points of contact and intermediate spaces of contraflexure for the rails, and adjustable means for forming a plurality of spaced points of contact between said base portion of said combined chair and fish-plate member and the under side of the base flanges of said rails, said means being mounted below said projections on said fish-plates. 110

4. A rail joint comprising, in combination, a pair of rails, a combined chair and fish-plate member connecting said rails, said combined chair and fish-plate member comprising a base portion and fish-plate portions, said fish-plate portions having inwardly extending portions overlying the base flanges of said rails and upstanding web engaging portions, said inwardly extending portions of said fish-plate portions overlying the base flanges of said rails being provided with alternate projections and depressions so as to form definite points of contact and intermediate spaces of contraflexure for the rails, and adjustable means for forming a plurality of spaced points of contact between said base portion of said combined chair and fish-plate member and the under side of the base flanges of said rails, said means being mounted below said projections on said fish-plates. 120

130

- portions having inwardly extending portions overlying the base flanges of said rails and upstanding web engaging portions, said inwardly extending portions of said fish-plate
- 5 portions overlying the base flanges of said rails being provided with alternate projections and depressions so as to form definite points of contact and intermediate spaces of 40 contraflexure for the rails and vertically ad-
- 10 justable means for forming a plurality of spaced points of contact between said base portion of said combined chair and fish-plate member and the under side of the base flanges of said rails, one of said means being mounted 45
- 15 under the juncture point of said rails so as to underlie both of said rails, said last named means being adapted to be independently adjusted vertically under said respective rails. 50
5. A rail joint comprising, in combination,
- 20 a pair of rails, a combined chair and fish-plate member connecting said rails, said combined chair and fish-plate member comprising a base portion and integral fish-plate portions, said fish-plate portions having inwardly extend- 55
- 25 ing portions overlying the base flanges of said rails and upstanding web engaging portions, said inwardly extending portions of said fish-plate portions overlying the base flanges of said rails being provided with alternate pro- 60
- 30 jections and depressions so as to form definite points of contact and intermediate spaces of contraflexure for the rails, said fish-plate portions being provided with a plurality of open- 65
- 35 ings adjacent their juncture with said base portion of said chair and fish-plate member
- and the openings in one fish-plate being in alinement with the openings in the other fish-plate, said openings being located below the projections on said fish plates, oppositely directed wedge members positioned in said 40 openings in said fish-plates and extending between the base flanges of said rails and the base portion of said combined chair and fish-plate member, one of said openings in each of said fish-plate portions being in line with the juncture point of said rails and three of said wedge members being positioned in said 45 openings, said last named wedge members consisting of a lower single wedge member and a pair of upper wedge members arranged 50 side-by-side on said lower wedge member, one on each side of the juncture point of said rails whereby said upper wedge members may be independently adjusted to elevate said rails.
6. A rail joint comprising, in combination,
- a pair of rails, a fish-plate member connecting said rails, said fish-plate member having inwardly extending portions overlying the base flanges of said rails and upstanding web en- 55
- gaging portions, said inwardly extending por- 60
- tions of said fish-plate portions overlying the base flanges of said rails being provided with alternate projections and depressions so as to form definite points of contact and intermediate spaces of contraflexure for the rails. 65

In testimony whereof, we have hereunto set our hands.

JAMES K. BOYD.
FRANK F. SLICK.
